UNITED STATES PATENT OFFICE.

FRANK JOSEPH BAUME, OF MULHOUSE, ALSACE-LORRAINE.

SHUTTLE-MOVER.

1,373,705.

Specification of Letters Patent.

Patented Apr. 5, 1921.

Application filed November 29, 1920. Serial No. 427,107.

To all whom it may concern:

Be it known that I, FRANK JOSEPH BAUME, a subject of Alsace-Lorraine, and a resident of Mulhouse, Alsace-Lorraine, have 5 invented certain new and useful Improvements in Shuttle-Movers, of which the following is a specification.

My present invention relates particularly to shuttle moving means of looms, and aims 10 to do away with the usual means actually in engagement with the shuttle for moving the same and to bring about various advantages not only in construction of looms but in construction of shuttles, by the application 15 of shuttle moving means which will effect the desired results as far as movement of the shuttle is concerned without actually engaging therewith.

In the accompanying drawings which 20 illustrate my present invention and form a part of this specification,

Figure 1 is a detail side view illustrating the parts proposed by my invention,

Fig. 2 is a bottom plan view of a shuttle 25 of one construction,

Fig. 3 is a detail side view of a portion of a shuttle and its race-way adjacent to one end of the latter,

Fig. 4 is a vertical transverse section 30 taken substantially on line 4—4 of Fig. 1,

Fig. 5 is a view illustrating a modified form of electro-magnet and carriage,

Fig. 6 is a detail perspective view of a shuttle race-way of one form, and

Fig. 7 is a detail perspective view of a 35 portion of a shuttle race-way of another form.

Referring now to these figures my invention proposes the use of a shuttle 10 which 40 may be of various constructions and of materially less complication than shuttles at present used which are engaged at their ends by the means serving to move the shuttle in operation, the only requirement 45 of my invention as regards the shuttle being that it shall be constructed either in part or in whole of magnetically attractive material. The most simple form of this arrangement and the one possibly to be pre-

ferred is the shuttle shown in Figs. 1, 2 and 50 3 whose body may be formed of any material having attached lengthwise upon its base a centrally disposed strip 11 of magnetically attractive material, the body being 55 for instance formed of wood and the strip 11 secured thereto by attaching screws

12. In this instance the loom with its lower strip 11 forms its own guide in the race-way 13 of a lay having a lengthwise slot 14, in which the strip 11 moves to prevent lateral displacement of the shuttle. The race-way may be provided with upright side flanges 15 but is preferably without such flanges as seen in Fig. 7 in particular so that by providing the surface of the raceway with transverse grooves, the latter 60 may receive warp threads and in this way permit the shuttle to move over such threads as are disposed in the grooves, without touching the same. The ends of the race-way may be provided with upright flanges 65 16 as in Fig. 3 carrying shock absorbing springs 17 with which the ends of the race-way may contact, and it is obvious from the foregoing that with the shuttle strip 11 exposed to the space below the race-way 70 through its slot 14 and the race-way itself formed of non-attractable material, the shuttle may be controlled in its movement by a lower electro-magnet 18 which I have 75 shown in Figs. 1 and 4 as mounted upon a carriage 19, the latter having rollers 20 arranged in vertically opposing pairs at opposite sides of its front and rear portions to engage the upper and lower surfaces of 80 spaced parallel tracks 21, this construction preventing movement of the electro-magnet 18 either toward or away from the shuttle by arranging the tracks 21 parallel with and below the race-way 13 as it is proposed to do. 85 A permanently spaced relation between the electro-magnet and the shuttle is thus brought about so that by maintaining proper electrical connections with the windings 22 of the electro-magnet, uniformly 90 efficient operation can be maintained.

In instances where it is not possible to utilize the electro-magnet upon a carriage 95 19, the electro-magnet itself, indicated generally at 23 in Fig. 5 may be provided with a depending portion 24, preferably insulated therefrom and provided with rollers 25 similar to the before described rollers 20, engaging tracks 26 positioned and constructed like the tracks 21.

My invention does not contemplate any particular manner of moving the electro-magnet with its carriage as a number of different connections may be made with the moving parts of the loom depending upon 100 the particular type of the loom, for bringing this movement about, and the choice of 105 110

means for this purpose is obviously not limited by any means such as the choice is limited at the present time in connection with shuttle engaging means for moving the shuttle.

5 I claim:

1. In looms, a shuttle having a lower lengthwise strip of magnetically attractive material, a race-way on which the shuttle is 10 movable having a lengthwise slot into which the said strip of the shuttle projects for guiding the shuttle, a track parallel with and below the race-way, and a carriage movable in guided relation on the track and

having electro-magnetic means spaced below the race-way to attract the shuttle. 15

2. In looms, a shuttle having a lower lengthwise strip of magnetically attractive material, a lengthwise slotted race-way on which the shuttle is movable having trans- 20 verse surface grooves to receive warp threads, and into the slot of which the magnetically attractive strip of the shuttle extends and forms a guide, and electro-magnetic means having guided movement 25 parallel with and spaced below the race-way for attracting the shuttle.

FRANK JOSEPH BAUME.
